L. WYANT

MECHANISM FOR CONTROLLING RAILWAY SWITCHES

Filed April 21, 1927

UNITED STATES PATENT OFFICE.

LEROY WYANT, OF CHICAGO, ILLINOIS.

MECHANISM FOR CONTROLLING RAILWAY SWITCHES.

Application filed April 21, 1927. Serial No. 185,440.

My invention relates to mechanism for controlling railway switches, and particularly to the locking apparatus usually embodied in such mechanism.

5 I will describe one form of switch mechanism embodying my invention, and will then point out the novel features thereof in claims.

In the accompanying drawing, Fig. 1 is a 10 perspective view of one form of mechanism embodying my invention. Fig. 2 is a view, partly sectioned and partly in elevation, of a portion of the apparatus shown in Fig. 1. Fig. 3 is a sectional view on the line III—III 15 of Fig. 2.

Similar reference characters refer to similar parts in each of the several views.

Referring first to Fig. 1, the reference character S designates a railway switch comprising two movable point rails 1 and 2 secured together by means of a tie rod 3 and operated by a rod 7. The tie rod 3 carries a lug 3^a through which the operating rod 7 passes, and this rod co-operates with two springs 4 and 5 placed on opposite sides of the lug 3^a, so that when the rod 7 is moved in either direction one of the springs 4 or 5 is compressed in order to forcibly move the point rails to one position or the other 25 against the associated stock rails. A damping device D is connected by a rod 6 with the lug 3^a to prevent flopping of the point rails when a train trails through the switch in normal position. The point rails 1 and 2 are 30 also connected together by means of a front rod 24^a to which is connected a lock rod 24. For the purpose of throwing the switch I provide a switch stand comprising a suitable base carrying a switch stand top 10. The top 35 has two notches 11 and 12 in the periphery thereof, and these notches co-operate with a switch operating lever 9 to hold the latter in position. The switch operating rod 7 is connected by means of a crank 8 and a 40 sleeve 8^a to an arm 8^b which carries the lever 9 pivotally connected therewith at 9^b. Arm 8^b and sleeve 8^a are secured together by a pin K. A target rod 17 passes vertically through the switch stand top 10 and sleeve 8^a, and 45 carries a key 17^a which co-operates with a key way 8^c in the sleeve 8^a, thus requiring that sleeve 8^a and rod 17 must rotate together but permitting rod 17 to move up and down independently of sleeve 8^a. With this arrangement it will be clear that when lever 9 50 is raised out of the notch 12 it may be rotated

through an angle of 90 degrees until it registers with the notch 11, and that this rotation will move the rod 7 so as to reverse the switch S.

In addition to operating the switch rod 7, the switch lever 9 is so arranged that each time it is swung out from one of the notches in the switch stand top 10, a plunger lock rod 21 is thrown from the left to the right, as 60 viewed in Fig. 2. For the purpose of accomplishing this movement the arms 8^b carries a pivot mounting 14 about which is pivoted a bell crank lever 15. The lever 15 may be operated in one direction or the other by means 65 of an angular member 13, the horizontal portion of which slides within a guideway which is cut out from the arm 8^b, and the projecting end of this horizontal portion carries a roller 13^a which co-operates with a cam surface 9^a on the upper end of switch operating lever 9. The vertical portion of the member 13 is slotted at 13^c and co-operates with a pin 13^b, which is mounted in one arm of the bell 70 crank lever 15. Secured to the target rod 17 75 is a pin 16, which co-operates with a slot 16^a in the other arm of the bell crank lever 15, so that when the lever 9 is swung to the horizontal position about the pivot 9^b, the arm 13 is pushed to the left (Fig. 2) and operates 80 through the bell crank lever 15 to push the target rod 17 downwardly. Secured to the lower end of target rod 17 is a stirrup 18 by means of which the target rod is connected to a second bell crank lever 19 pivoted in any 85 suitable manner at a point 20, the lower arm of this lever 19 being pivotally connected with the right-hand end of plunger lock rod 21. It will now be apparent that operation 90 of the switch operating lever 9 will cause the plunger lock rod 21 to be drawn toward the right, as viewed in Fig. 2, each time that the lever 9 is raised to the horizontal position.

For the purpose of locking the switch S in each position after it is thrown, the plunger lock rod 21 co-operates with the switch lock rod 24. When the rod 21 occupies the position shown in Fig. 2, it passes through a hole in the rod 24 and prevents the switch from being thrown in either direction. When the 100 rod 21 is withdrawn, the lock rod 24 is free to move from one position to the other under the action of the switch operating lever 9.

The lock rod 21 co-operates with the usual plunger lock circuit controller C in such manner that a contact 25—26 is closed or open according as the lock rod is in its locking or its 110

unlocking position. The structure and operation of this circuit controller form no part of my present invention.

Associated with the plunger lock rod 21 is a housing 23 carrying tripping mechanism which I provide for the purpose of allowing the switch S to remain unlocked in its normal position after lever 9 is returned to notch 12. Secured to the plunger lock rod 21 within the housing 23 is a head 51 which cooperates with a spring 30 for the purpose of biasing the plunger rod to its left-hand position. Also secured to the rod 21 is a member 52 to which is pivoted one arm of a toggle 31, the other arm of this toggle being pivotally secured to the housing 23 at point 55. The toggle arms are pivotally connected at point 49. Under normal conditions the toggle 31 occupies the full-line position to which it is biased by the spring 30 pushing against the head 51, but when the plunger lock rod 21 is withdrawn in the right-hand direction, the toggle straightens out into the position shown in dotted lines, and under certain conditions may move to a position below dead center, so that it will remain in this position independently of the action of spring 30. Secured to the pivot point 49 of the toggle is a straight link 32 pivotally connected at 50 to a link 33 which is provided with a long narrow slot 34. The link 33 is movable up and down in co-ordination with the toggle 31 and is guided in this movement by two anti-friction rollers 39 and 40 mounted on opposite sides of the path of travel of the link. Pivotally mounted in the casing 23 at 35 is an arm 36 to one end of which is secured a counterweight 37. When this arm occupies its normal position, as shown in full lines, a pivot pin 38 carried near the left end of this arm occupies a position near the top of slot 34 in link 33 so that owing to the weight of counterweight 37 it is impossible to pull the toggle 31 and the associated mechanism below its dead center position, because the top of slot 34 will engage the pin 38 in arm 36 and prevent such movement. When the arm 36 is moved to the dotted line position, however, the toggle may be moved below its dead center position in which it will remain until released by operation of mechanism for allowing the arm 36 to return by gravity to its full line position. The left-hand end of arm 36 has a notch 56 which cooperates with a latch 41. This latch is pivoted at 42 in the casing 23 and carries at its lower end a roller 43 which is adapted to co-operate with the notch 56 in the end of the arm. A spring 44 normally biases the latch 41 to its right-hand position, but this latch may be moved to the left by means of a cam 47 (Fig. 3). The cam 47 is carried on one end of a shaft 46 mounted in a sleeve 45 forming part of the casing 23. Secured to the outer end of the shaft 46 is a trip arm 48 which

normally hangs in substantially a vertical position in proximity to the track rails. When the arm 48 is moved toward a horizontal position so that the cam 47 is rotated in a clockwise direction, as shown in Fig. 2, this cam moves the latch 41 to the left, so that the roller 43 is disengaged from the notch 56 and allows the arm 36 to drop to the full-line position under the action of counterweight 37. It will be apparent from the foregoing, that so long as the arm 36 occupies the full-line position, the plunger lock rod 21 cannot be locked in its right-hand position, because the toggle 31 cannot be moved below its dead center, due to the engagement of the pin 38 with the top of slot 34. It will, however, be apparent that when the arm 36 is moved to the dotted-line position, in which it is locked by the latch 41, the toggle 31 may be moved to its dotted line position, in which the pivot 49 is below dead center, and the spring 30 is then ineffective to move the rod 21 to the left. The parts are so arranged, however, that the rod 21 may be moved far enough to the right by lever 9 to release the lock rod 24 without the arm 36 being moved away from its full-line position.

As shown in the drawing, the switch S is in the normal position, and all parts of the mechanism are in the positions corresponding to this position of the switch. To reverse the switch, the lever 9 is raised to a horizontal position and rotated through an angular distance of 90°, and is then dropped into the notch 11, so that the switch is moved to its reverse position and locked. The movement of the lever 9 to the horizontal position will move the rod 21 to the right as viewed in Fig. 2, releasing the lock rod 24 and allowing the switch points 1 and 2 to be moved, but when the lever 9 is returned to its vertical position, the plunger rod 21 is moved to the left under the action of spring 30 so that the switch is locked. When, however, a train in siding P is to move out into the main line, the points being set for the main track, the following operations are performed: The train first stops before the engine reaches the switch S in coming from the siding P, and the head-end brakeman dismounts from the train and raises the arm 36 to the horizontal position in which it is locked by the latch 41. This frees the link 33, so that when the switch operating lever 9 is raised to the horizontal position to pull the plunger rod 21 to the right and so to unlock the rod 24, the toggle 31 is allowed to move to its position below dead center. The brakeman may then return the lever 9 to its vertical position in notch 12, leaving the switch in its normal position but unlocked. The brakeman now returns to the train and the train advances through the switch, the points 1 and 2 of the switch being moved to the reverse position by the action of the flanges of the front wheels of the first car 130

which reaches the switch. As the point rails 1 and 2 move to their reverse positions, the spring 5 is compressed so that when the front truck of the train passes the point rails this 5 spring will tend to return the point rails to the normal position but will be prevented from doing so by the action of the damping device D. The switch, therefore, will not return to its normal position during the passage 10 of the train. Ordinarily in making such a movement, it is necessary for the rear-end brakeman to lock the switch after the train passes through it, and so it is necessary for the train to make a second stop. I avoid the 15 necessity for this second stop by providing the lever 48, which is mounted adjacent the trackway in a position such that it may be swung by the rear-end brakeman as the train leaves the switch or may be operated by an 20 arm provided on the caboose for this purpose. As the train leaves the switch the brakeman moves the arm 48 to a horizontal position by rotating it in a counter-clockwise direction as seen in Fig. 1, so that the cam 47 releases the 25 latch 41, allowing the arm 36 to swing to the full-line position under the action of counter-weight 37. This raises the toggle 31 above the dead center position due to the engagement of pin 38 with the top of slot 34, and the plunger lock rod 21 is moved to the left-hand position 30 under the action of spring 30 as soon as the spring 5 moves the switch point rails 1 and 2 far enough to bring the lock rod 24 to such a position that the hole through this rod coincides with the path of travel of the rod 21. Suitable means may be provided for indicating 35 whether or not the switch is locked after the train passes through it, and such indicating mechanism may be controlled in any suitable manner by the contacts 25 and 26 of the plunger lock circuit controller.

It will now be clear that apparatus embodying my invention eliminates one stop during movements through a switch from the siding 45 into the main line, and also provides means whereby the position of the switch may be checked. It will also be clear that the apparatus does not in any way interfere with the normal operation of the switch for other 50 movements, since the switch stand may be operated in the usual manner independently of the tripping mechanism in casing 23.

Although I have herein shown and described only one form of railway switch operating mechanism embodying my invention, it is understood that various changes and modifications may be made therein within the scope of the appended claims without departing from the spirit and scope of my invention.

Having thus described my invention, what I claim is:

1. In combination, a railway switch, means for moving said switch to a normal or a reverse position, means for locking the switch, 65 means for restraining the locking means to

permit trailing train movements through the switch, and a tripping device operable from the train for releasing the locking means to lock the switch after the train leaves the switch. 70

2. In combination, a railway switch having a normal and a reverse position, means for moving said switch to a normal or a reverse position, means for locking said switch in either position, means for restraining said 75 locking means during trailing train movements through the switch, and means operable from a train for releasing said restraining means.

3. In combination, a railway switch having 80 normal and reverse positions, means for moving said switch to either of such positions, means for locking said switch in either of its positions, means for rendering the locking means ineffective during trailing train movements through the switch in normal unlocked 85 position, resilient means for biasing the switch to normal position during such movements, and means operable from the train for rendering the locking means effective to lock the 90 switch when a train leaves the switch.

4. In combination, a railway switch having normal and reverse positions, means for moving said switch to either of such positions, means for locking said switch in either 95 of its positions, means for rendering said locking means ineffective during trailing train movements through the switch, and means operable from the train for rendering said locking means effective to lock said switch 100 after such a train movement through the switch.

5. In combination, a section of railway track comprising a main line and a turn-out, a spring switch leading into the turn-out, 105 means for moving said switch to a normal or a reverse position, means for locking said switch, means for rendering said locking means ineffective during trailing train movements through the switch, and tripping means 110 operable from the train for rendering said locking means effective to lock said switch in normal position automatically after such train movements through the switch.

6. In combination, a railway switch, means for moving said switch to a normal or a reverse position, a reciprocable rod for locking said switch in either position, means for biasing said rod toward its locking position, means for holding said rod in its unlocking position against said bias, a pivoted lever for controlling the holding means, means for locking said lever in a position to allow said holding means to become effective, and means operated by said lever for releasing 120 said holding means. 125

7. The combination with a spring switch and means for damping its movement toward normal position, of a reciprocable locking rod, means for biasing said rod to its locking 130

position, a toggle for holding said rod in its unlocking position, gravity operated means for releasing said toggle, a latch for restraining the operation of the gravity operated means, and means operable from a train passing through the switch for releasing said latch and automatically locking said switch in normal position.

8. The combination with a spring switch and means for damping its movement toward normal position, of a reciprocable locking rod, means for biasing said rod to its locking position, a toggle for holding said rod in its unlocking position, gravity operated means for releasing said toggle, a latch for restraining the operation of the gravity operated means, a cam for operating said latch, and a lever mounted adjacent the switch for operating said cam to release the latch.

9. In combination, a railway switch, a locking rod biased to a position in which such rod prevents movement of the switch, means including a toggle for holding said locking rod in its unlocking position against said bias, gravity operated means for releasing said toggle, a latch for restraining the operation of the gravity operated means, and means operable from a train passing through said switch for releasing said latch.

10. In combination, a railway switch, a locking rod biased to a position in which such rod prevents movement of the switch, means including a toggle for holding said locking rod in its unlocking position against said bias, gravity operated means for releasing said toggle, a latch for restraining the operation of the gravity operated means, a cam for operating said latch, and a lever

mounted adjacent the switch for operating the cam to release the latch.

11. In combination, a railway switch, manually operable means for moving said switch to its normal or reverse position, a locking rod attached to said switch, a plunger biased to a position in which the plunger prevents movement of said locking rod, means for moving said plunger to an ineffective position against such bias, a manually operable arm biased to one position, means for moving the arm to a second position against its bias, means effective when said arm occupies its second position to hold said plunger in its ineffective position, and a manually controlled latch for at times holding said arm in said second position.

12. In combination, a railway switch, a manually operable lever for controlling said switch, a locking rod controlled by said lever for preventing movement of said switch, a device for at times rendering said locking rod ineffective to prevent movement of the switch, and a second lever operable from a train passing through said switch for rendering said device ineffective.

13. In combination, a railway switch, a manually operable lever for controlling said switch, a locking rod controlled by said lever for preventing movement of said switch, a latch, means controlled by said latch for at times rendering said locking rod ineffective to prevent movement of the switch, and a second lever operable from a train passing through said switch for at times releasing said latch.

In testimony whereof I affix my signature.
LEROY WYANT.
